(57) **CLAIM**

The ornamental design for a vehicle display screen or portion thereof with graphical user interface, as shown and described.

DESCRIPTION

This application contains subject matter related to the following co-pending U.S. design patent applications:

Application Ser. No. 29/747,142, filed herewith and entitled “Vehicle Display Screen or Portion Thereof with Graphical User Interface”;

Application Ser. No. 29/747,143, filed herewith and entitled “Vehicle Display Screen or Portion Thereof with Graphical User Interface”; and

Application Ser. No. 29/747,146, filed herewith and entitled “Vehicle Display Screen or Portion Thereof with Graphical User Interface”.

The sole FIGURE is a front view of a vehicle display screen or portion thereof with graphical user interface according to the design.

The broken line showing of the vehicle display screen is provided for the purpose of illustrating environmental structure and forms no part of the claimed design.
